UNITED STATES PATENT OFFICE.

SAMUEL ORKIN, OF CHELSEA, MASSACHUSETTS, ASSIGNOR TO INTERNATIONAL BATTLESHIP COMPANY, OF BOSTON, MASSACHUSETTS, A CORPORATION OF MAINE.

GUN FIRING MECHANISM.

1,248,536.

Specification of Letters Patent.

Patented Dec. 4, 1917.

Application filed April 23, 1917. Serial No. 164,275.

To all whom it may concern:

Be it known that I, SAMUEL ORKIN, a subject of Russia, and a resident of Chelsea, in the county of Suffolk and Commonwealth 5 of Massachusetts, have invented certain new and useful Improvements in Gun Firing Mechanisms, of which the following is a specification.

This invention relates to mechanisms for 10 operating firearms at predetermined times, and has for its particular object the production of a device to be used in the turret of a toy battleship in which the miniature guns coact with suitable firing mechanisms 15 located within the turrets whereby the oscillation of said turrets will cause the guns to be fired.

The invention consists in an oscillating 20 turret having located therein the body portions of one or more firearms the muzzles of which project from said turret, each firearm being provided with trigger or other firing device adapted to be operated by the oscillation of the turret.

25 The invention further consists in certain novel features of construction and arrangement of parts which will be fully understood by reference to the description of the drawings and to the claims hereinafter given.

Of the drawings:

Figure 1 represents a horizontal section 30 through a turret and showing in plan a battery of guns or firearms and the operating mechanisms for oscillating the turret and incidentally firing the guns.

Fig. 2 represents a vertical section of the same, the cutting plane being on line 2—2 on Fig. 1.

40 Fig. 3 represents a vertical section of the same, the cutting plane being on line 3—3 on Fig. 1.

Fig. 4 represents a horizontal section the cutting plane being on line 4—4 on Fig. 2.

45 Similar characters designate like parts throughout the several figures of the drawings.

In the drawings, 10 is a part of the stationary frame-work of a device such as a 50 toy battle-ship. Superimposed upon this framework 10 is a circular support 11 and depending from said framework 10 is a bracket 12. Revolubly mounted in the bracket 12 is a vertical shaft 13 having secured to its lower end a sprocket wheel 14

and to its upper end a crank 15. Meshing with the sprocket wheel 14 is a sprocket chain 16 by which the shaft 13 is adapted to be rotated. The crank 15 has pivoted thereto one end of a link 17, the opposite end of which is pivotally connected at 18 to a rack member 19 adapted to be reciprocated during each rotation of the crank 15. This rack 19 meshes with the pinion 20 secured to a sleeve 21 surrounding a vertical shaft 22 immovably secured at its lower end to a bracket 23 depending from the frame 10. The upper end of the sleeve 21 has secured thereto the bottom plate 24 of the turret 25, this bottom plate being provided with the depending annular flange 26, the lower beaded end of which rests in an annular groove on the upper face of the support 11.

When the rack 19 is reciprocated the turret 25 will be oscillated through the medium of the sleeve 21 and the pinion 20 meshing with said rack 19. The bottom plate 24 has secured thereto the upwardly extending parallel flanges 27 connected at one end by 75 the cross plate 28. Superimposed upon the cross plate 28 are the handles 29 of two revolvers 30 horizontally positioned with their trigger guards 31 abutting each other. The barrels 32 of these revolvers are supported in a cross member 33 and each barrel has secured thereto by means of the screw 34 a supplemental barrel 35 extending through a port 36 in the front of the turret 25. These supplemental barrels 35 are 80 formed in the shape of heavy guns such as are ordinarily used in the turret of a battle-ship. A similar supplemental barrel 37 corresponding in shape to the barrels 35 is positioned between the barrels 35 and extends through a port 38 in the turret 25 and is secured by means of the screw 39 to a support 40 interposed between the parallel flanges 27. Each revolver is provided with the usual cylinder 41, hammer 42, and trigger 43, and the firing mechanism thereof 85 operates in the usual manner. Pivoted at 44 to each flange 27 is a trigger operating member 45 extending upwardly through the trigger guard 31 in contact with the trigger 43. Contacting with each trigger operating member 45 is an adjustable member 46 threaded to an ear 47 formed upon a plate 48 secured to and extending transversely of a slid able member 49 having slots 110

110

50 and 51 formed therein in which are positioned respectively the block 52 secured by the screw 53 to the cross member 28 and the hub 54 of a crank disk 55 pinned to the upper end of the shaft 22.

5 Pivoted at 56 to the crank disk 55 is a link 57 the opposite end of which is pivoted at 58 to the slidable member 49. In the operation of the device the cylinders 41 are loaded with blank cartridges and the hammers 42 are cocked as indicated in Fig. 1 of the drawings.

10 The pivotal connection 56 between the disk 55 and the link 57 is normally located as indicated in Fig. 1 of the drawings. If the turret is moved contra-clockwise the slidable member 49 will be moved to the right of Fig. 1, but if the turret is moved clockwise this slidable member 49 will be 20 moved to the left and cause the adjustable members 46 to move the trigger operating members 45 about the pivots 44, thereby actuating the triggers and causing the firearms to fire simultaneously.

25 After each of the guns have been fired the hammers must be cocked again before a second firing may occur, although it is obvious that self-cocking firearms may be used, in which case the firearms will continue to be fired until all of the cartridges in the cylinder 41 have been expended.

30 It is believed that the operation and many advantages of this invention will be fully understood from the foregoing description.

35 Having thus described my invention, I claim:

1. In a device of the class described, the combination of a firearm provided with a 40 hammer and a trigger; an oscillating support therefor; a trigger operating member; and automatic means for controlling the operation of said trigger operating member by the oscillation of said support.

45 2. In a device of the class described, the combination of a firearm provided with a hammer and a trigger; an oscillating support therefor; a trigger operating member pivoted thereto; a reciprocating member 50 carried by said support and adapted to move said operating member about its pivot; and means for reciprocating said reciprocating member by the oscillation of said support.

55 3. In a device of the class described, the combination of a firearm provided with a hammer and a trigger; an oscillating support therefor; a trigger operating member pivoted thereto; a reciprocating member 60 carried by said support; an adjustable member carried by said support and adapted to move said operating member about its pivot; and means for reciprocating said reciprocating member by the oscillation of said support.

4. In a device of the class described, the combination of a firearm provided with a hammer and a trigger; an oscillating support therefor; a trigger operating member carried thereby; a reciprocating member on 70 said support provided with projections adapted to coact with said trigger operating member; a fixed crank about the axis of which said support is adapted to oscillate; and a link between said crank and 75 reciprocating member.

5. In a device of the class described, the combination of a firearm provided with a hammer and a trigger; an oscillating support therefor provided with a tubular hub; 80 a trigger operating member carried thereby; a reciprocating member on said support provided with projections adapted to coact with said trigger operating member; a fixed crank having a shaft extending 85 through said hub and about the axis of which said support is adapted to oscillate; a link between said crank and reciprocating member; a gear on said tubular hub; and a rack meshing with said gear. 90

6. In a device of the class described, the combination of a firearm provided with a hammer and a trigger; an oscillating support therefor provided with a tubular hub; a trigger operating member carried thereby; 95 a reciprocating member on said support provided with projections adapted to coact with said trigger operating member; a fixed crank having a shaft extending through said hub and about the axis of which said support is adapted to oscillate; a link between said crank and reciprocating member; a gear on said tubular hub; a rack meshing with said gear; a revoluble disk; and a connector between said disk and said 100 rack.

7. In a device of the class described, the combination of a firearm provided with a hammer and a trigger; an oscillating support therefor provided with a tubular hub; a trigger operating member carried thereby; a reciprocating member on said support provided with projections adapted to coact with said trigger operating member; a fixed crank having a shaft extending through 11 said hub and about the axis of which said support is adapted to oscillate; a link between said crank and reciprocating member; a gear on said tubular hub; a rack meshing with said gear; and revoluble 111 means for imparting reciprocatory movement to said rack.

8. In a device of the class described, the combination of a firearm provided with a hammer and a trigger; an oscillating support therefor provided with a tubular hub; a trigger operating member carried thereby; a reciprocating member on said support provided with projections adapted to coact with said trigger operating member; a fixed 12 121

crank having a shaft extending through said hub and about the axis of which said support is adapted to oscillate; a link between said crank and reciprocating member; a gear on said tubular hub; a rack meshing with said gear; a revoluble disk; a connector between said disk and said rack; a shaft for said disk; a sprocket wheel thereon; and a chain to drive said sprocket wheel.

9. In a device of the class described, the combination of a fixed cylinder; a support mounted thereon provided with a tubular hub centrally positioned in said cylinder; means coacting with said hub adapted to

oscillate it; a fixed shaft extending through said hub; a crank secured to the upper end of said shaft; a member slidable on said support provided with a projection; a link between said crank and slidable member; a trigger operating member on said support in the path of said projection; and a fire-arm secured to said support and provided with a trigger and a hammer.

Signed by me at Washington, District of Columbia, this 28th day of March, 1917.

SAMUEL ORKIN.
